UNITED STATES PATENT OFFICE.

FRANK JENISON MAIN, OF MADISON, WISCONSIN.

FASTENER FOR THE MEETING-RAILS OF SASHES.

SPECIFICATION forming part of Letters Patent No. 424,990, dated April 8, 1890.

Application filed November 23, 1889. Serial No. 331,294. (No model.)

To all whom it may concern:

Be it known that I, FRANK JENISON MAIN, a citizen of the United States, residing at Madison, in the county of Dane and State of Wisconsin, have invented certain new and useful Improvements in Sash-Locks; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a front elevation of a portion of a window with my improved sash-lock applied thereto. Fig. 2 is a vertical section of the same on the plane of line 1 1. Fig. 3 is a vertical section on the line *m m* of Fig. 1. 20 Fig. 4 is a top view of the locking-bolt.

The object of my invention is to produce a simple strong automatic locking-bolt which, in connection with an automatic clasping device, may be readily attached to window-sash.

25 A is the window-frame.

B and B' are the upper and lower sashes.

C is the bottom rail of the upper sash.

D is the center bar of the sash.

30 D' D' are panes of glass.

On the top of the lower sash, and in line with the center bar D of the upper sash, is secured by screws *a a* the standard E, in which slides a loose locking-bolt F, and from 35 the upper end of which hangs a pendent bolt-keeper G, so as to bear upon the outer end of the sliding bolt F, the standard being perforated near its top at *b* for the reception of the pivotal end of the pendent bolt-

40 keeper and at *c* for the reception of the loosely-sliding bolt F. The head *e* of this bolt is triangular, as shown, and a triangular recess *d* is cut in the front face of the standard E for its reception.

45 A keeper *f* with an incline on its upper and a shoulder on its lower end and one or more keepers *h* with inclines at both ends and a recess or socket between them are secured to the upper sash directly in line with

bolt F, as shown in Figs. 1 and 2. The bolt 50 F is long enough to project underneath the keeper *f* or into recess *g* of the keepers *h*.

To draw the sash together closely at the same time that they are automatically locked, an upright wedge-shaped tongue of metal *i* 55 is secured to the top of the bottom rail C of the upper sash, and a clasp *k*, with a wedge-shaped open mouth, is secured to the upper rail of the lower sash. When they come together, they hold the sash close together laterally, while the bolting device prevents any vertical movement.

The pendent bolt-keeper is made in the form shown in the drawings, having a curved cut-away portion on its inner face *l* as a 65 bearing-surface for the head of the bolt F, and inwardly-inclined sides next to the expanding triangular head of the bolt, so as to receive, in connection with the bolt, the pressure of the thumb and one finger of the operator when unlocking the bolt or setting the sash.

These devices are supposed to be attached to sash that are suspended and move freely. When in position, the pendent bolt-keeper is 75 bearing automatically all the time on the head of the sliding bolt and pressing it against the sash. The automatic operation of the devices takes place as the sash come together. The pendent keeper allows the bolt to slide 80 over the incline of the keeper *f* on the sash, and after passing forces it underneath its head, the tongue *i* at the same time being hugged by the clasp *k*, and the sash are locked against both side and vertical movement. 85 There may be one or more of the keepers *h* secured to the sash, and thus admit of their being locked at any desired height. The bolt, however, will not enter the recesses only when the sash are moved slowly.

90 It will readily be seen that my device is simple, strong, and easily applied to the sides or the center of any window-sash. No springs are needed, and the locking-bolt with its pendent keeper perform their individual functions separately, and the locking is done automatically as the sash are moved into the desired positions.

What I claim as new, and desire to secure by Letters Patent, is—

1. An automatic sash-lock consisting of a standard E, with a loose sliding bolt F, and 5 a pendent weighted bolt-keeper G, attached as shown, in combination with keeper f, as and for the purpose herein set forth.

2. The combination of standard E, provided with the loose sliding bolt F and pendent

bolt-keeper G, with keepers h, with inclines to at both ends and intervening socket, as and for the purpose set forth.

In testimony whereof I affix my signature in presence of two witnesses.

FRANK JENISON MAIN.
